(57) **CLAIM**

The ornamental design for a canopy fixed weighting device as shown and described.

DESCRIPTION

FIG. 1 is a rear, left and top perspective view of a canopy fixed weighting device, showing my design.

FIG. 2 is a front, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view of the canopy fixed weighting device of FIG. 1; and,

FIG. 8 is an enlarged bottom plan view of the canopy fixed weighting device of FIG. 1.

The broken lines depict portions of the canopy fixed weighting device that form no part of the claimed design.

1 Claim, 8 Drawing Sheets
